UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

ELECTRICALLY-CONTROLLED SORTING-MACHINE.

1,376,556.

Specification of Letters Patent.

Patented May 3, 1921.

Application filed June 10, 1919. Serial No. 303,155.

To all whom it may concern:

Be it known that I, WILLIAM W. LASKER, a citizen of the United States, residing in Brooklyn, in the county of Kings and State 5 of New York, have invented certain new and useful Improvements in Electrically-Controlled Sorting-Machines, of which the following is a specification.

This invention relates to machines for 10 sorting perforated cards of the kind used in automatic accounting and calculating machines, in which cards are passed from the card analyzer and deflected into the appropriate compartments by deflectors which 15 are not operated until the card reaches the deflector.

The invention relates more particularly 20 to improvements in the sorting machine described in my U. S. Patent No. 1,315,370, issued Sept. 9th, 1919, for sorting machines.

One object of the invention is to provide 25 an efficient electric means associated with each compartment to the exclusion of the others for controlling each deflector by the card in the analyzer destined to be deflected by such deflector into the associated compartment.

While herein I describe minute details of 30 the invention, the invention is not limited to these, since the features of construction and combination may be greatly varied without departing from the scope of the invention as claimed.

In the accompanying drawing showing by 35 way of example, two of many possible embodiments of the invention—

Figure 1 is a side elevation of the machine:

Fig. 2 is an enlarged fragmental perspective view showing the timing arrangement;

Fig. 3 is a face view of a timing disk with the settable cams thereon;

Fig. 4 is a sectional view taken through the setting means for setting the settable 45 cams, and

Fig. 5 is a face view showing the arrangement of another form of setting means.

As shown in Fig. 1, the machine comprises a base 10 on which are mounted a 50 pair of side plates 11 on which are mounted the card feeding means 12, the analyzer 14 and other parts of the mechanism to be mentioned. The card feeding means 12 of the analyzer 14 are similar in construction

to that described in the U. S. Patent to 55 James Powers, No. 1,282,626, issued Oct. 22nd, 1918, and the U. S. Patent to W. W. Lasker, No. 1,298,971, issued April 1st, 1919; hence they need not now be shown or described in all their details.

The upper part of the feeding means comprises a magazine hopper 18 adapted to receive a pack of cards to be sorted; and at the lower part of the feeding means there is provided a reciprocating block 19 guided 65 in the lower part of the feeding means and connected by means of a link 20 to a lever arm 21 mounted on the shaft 24 carried between the side plates 11, and connected by the link 26 having its end 28 eccentrically 70 mounted on the eccentric shaft 29 suitably driven, as will be hereinafter described, from the motor 30, whereby the block 19 is reciprocated in the lower part of the magazine 18. The block 19 is provided with 75 a picker knife 34 whereby when the block is reciprocated the lowermost card in the magazine is fed forward through the micrometer slot 35 at the outlet side of the feeding means.

From the micrometer slot 35 the card is received between the roller 36 and a roller mounted on a shaft 38 suitably driven by the sprocket 40 and chain 41 or the like from the drive wheel 44 of the motor 30. 85 From the shaft 38 suitable gears 45, 46, and 47 convey power to the eccentric shaft 29 and to a conveyer roller coöperating with the conveyer rollers 49 and 50, which latter are adapted to withdraw the cards from the 90 analyzer 14 and deliver them to the conveying means to be later described.

The cards are conveyed by the roller 49 and the coöperating roller into place between the perforated plates 51 suitably supported on the side plates 11. The pin box 52 is disposed above the perforated plates 51 and is vertically reciprocated by means of links 58 having their lower ends receiving the eccentric 59 of the eccentric shaft 29. 100 The pin box is provided with rows of pins 65 which may be caused to register with any one of the rows of perforations of the plates 51 by means of suitable adjustments as explained in said last named copending 105 applications.

The pins 65, as explained in the first mentioned of said applications, are yieldably

- pressed against the perforated cards, and upon finding a perforation pass through the card during the downward motion of the pin box and are then locked into retrograde motion relative to the pin box, after which continued downward movement of the pin causes the pin to bear against one of the plungers 85 (Fig. 2) which correspond in number to the pins 65 and are 5 carried in suitable guide plates 86 transversely slidably mounted between the side plates 11, as explained in said last named copending applications. The plungers 85 when depressed by the analyzing pins, make 10 connection with the terminal 87 of the insulated electric wires 89, covered with insulation 90, for operating the selecting mechanism of the card conveyer as will be explained.
- 15 20 It is, of course, necessary that the plungers 85 always remain in register with the analyzing pins 65 as for instance when the pin box is adjusted so that the pins register with the row of perforations which are to be analyzed. These mechanisms, however, form 25 no part of the present invention and are described in detail in said last named application.
- 25 30 The cards are received from the roller 50 (Fig. 1) and are finally conveyed to the compartments 92 formed by transverse partitions 93 mounted at their lower ends upon the base 10 and having their upper ends secured to retaining pieces 95 carried upon 35 the bearing supports 96 mounted upon the lower edges of the extension plates 98 secured to the side plates 11. Rotatably mounted in said bearing supports 96 are a plurality of deflector shafts 99, one for each 40 compartment, on which are secured deflectors 100 (Fig. 2) formed of strips of material bent upon themselves and secured by means of rivets 101 to the deflector shaft. Upon each deflector shaft 99 there are 45 rotatably mounted a pair of lower guide rollers 102 against which are yieldably pressed the upper guide rollers 104 rotatably mounted in brackets 106 loosely mounted on pivot bolts 108 secured to the extension plates 98.
- 50 55 On each upper shaft 105 there is fixed a pinion 112 meshing with an idler 113 rotatably mounted on one of the bolts 108.
- The end bracket 114 is loosely mounted on a short bearing shaft 115 on which is 60 fixed a drive pinion 116 and a drive sprocket 117, the latter being driven by means of a sprocket chain 118, on the sprocket wheel 120 carried on the shaft 121 operatively connected to a gear wheel 122 in turn driven 65 from the gear 48. On the shafts 121 and 124 are mounted rollers 125 which receive the cards from the analyzing plates 51 and convey them to the rollers 102 and 104 which latter convey the cards in a horizontal path above the deflectors 100, when the deflectors

are in their normal horizontal position as shown in Fig. 2. When the deflectors 100 are deflected upwardly so that a card passing from the analyzing plate passes to the underside of the deflector, such card is deflected into one of the compartments 92 on to the receiving plate 127.

Means for operating the deflector will now be described.

Mounted upon one of the side plates 11 (Fig. 2) is a bracket support 130 upon which are mounted elbow brackets 131 provided with timing shaft bearings 132 and deflector shaft bearings 134, the latter receiving the ends of the deflector shafts 99. 70 In the bearings 132 there is disposed a timing shaft 135 on which are fixed, one for each compartment, a plurality of timing disks 136. Disposed around each timing disk equal angles apart, are a plurality of 75 tripping supports or pivots 137 on which are pivotally mounted settable tripping cams 138 provided at their inner edges with a cam projection 140. Said cams are held spaced from the disk by means of spacing 80 collars 141. At the free end of each settable cam there is secured a pivot pin 143 (Fig. 85 3) on which is pivotally mounted a detent 90 144 provided with an upwardly pointing releasing finger 145 and an inwardly pointing detent finger 146 provided with an active 95 detent shoulder 147 and an inactive detent shoulder 148 either one of which is adapted to rest upon the detent pin 150 mounted upon the disk. Said finger 144 is held pressed 100 against the detent pin by means of a coil spring 152 wrapped around the collar 141 and pressing against a projection 153 carried upon the detent 144.

Upon each pivot pin 143 there is also carried a tripping roller 155, adapted, when the active shoulder 147 engages the detent pin, to engage the operating arm 156 (Fig. 2) fixed upon the deflector shaft 99, whereby as said disk rotates and brings said roller into contact with said arm 156, the deflectors 100 are raised and deflect the cards into the compartments. After the operating arm 156 has been thus operated, the releasing finger 145 engages the releasing pin 158 carried upon the outer end of the operating arm 156, whereby said active shoulder 147 is forced away from the detent pin 150 and the spring 152 causes the tripping cam and detent to move inwardly until the detent pin 150 is engaged by the inactive shoulder 148. The deflector operating means as thus far described is shown in said first named application.

Each timing shaft bearing box 132 (Fig. 4) is provided with a reduced extension 160 on which is fixed by means of a set screw 161, a plunger bracket 162 provided with an opening receiving a threaded extension 163 of a thimble 164 held in place by a nut 165. 125 130

Said thimble is provided with a longitudinal bore 166 reduced at its inner end to form an annular shoulder 167.

In each bore there is disposed a sleeve 168 in which is slidably received an armature core 169 between which and said shoulder 167 there is disposed a coil spring 170 for holding the core retracted. To each core 169 there is fixed by means of a threaded connection a tripping or setting plunger 171 passing outwardly through said bore 166. Around said sleeve 168 is wound a solenoid 174 having one end 175 of its wire connected to the insulated electric wire 89 (Fig. 2). The other end of the solenoid wire is connected by the conductor 176 (Fig. 4) to one terminal of a suitable source of current 177, the other terminal thereof being, by means of the conductor 178, grounded on the frame of the machine. There is one solenoid 168 electrically connected by the wires 175 and 89 to each terminal 87 (Fig. 2). As the plungers 86 are grounded on the frame of the machine, it will be seen that whenever a plunger 85 is depressed to contact with a terminal 87, a circuit is formed comprising said plunger pin 85, the terminal 87, the wire 89, the end 175, the solenoid 168, the conductor 176, the source of current 177, the conductor 178, and the frame of the machine. When the circuit is thus formed by the depressing of a plunger 85, the corresponding solenoid is energized and the corresponding tripping or setting plunger 171 is projected.

The timing shaft 135 is rotated by means of bevel gears 180 (Fig. 1) driven by suitable gears 181 from the gear 47; and these gears are so proportioned that each time a card is analyzed in the analyzer, one of the tripping cams 138 is just coming into operative relation with one of the plungers 171.

When a card is in the analyzer and the analyzing pin 65 finds a perforation and presses upon the plunger 85 the solenoid projects the tripping plunger 171, whereupon, the tripping plunger engages the tripping cam 138 at that time coming into operative relation therewith.

As the various compartments 92 are placed progressively greater distances from the analyzer, it requires a greater length of time for the card passing from the analyzer to reach the compartments more remote therefrom; and provision is made for operating the deflector just at the instant that the card reaches it so that each card may be deflected into its appropriate compartment without having to wait until sufficient time has elapsed for a card to be deflected into the most remote compartment. In order to accomplish this it is merely necessary to place the plunger 171 associated with each compartment and timing disk

such a distance from the associated operating arm 156 that the tripping cam which comes into operative relation with such plunger at the time that the card is in the analyzer will have just time to pass from 70 such tripping plunger to said operating arm as the card which operated such plunger requires to pass from the analyzer to the deflector. In order to fulfill these conditions the plungers 171 must be placed 75 spirally around the timing shaft, the plungers associated with the most remote compartments being placed the greatest distances from the operating arm 156, such distances being measured forward from the 80 plunger in direction of rotation of the disks indicated by the arrow at the right of Fig. 2. As the embodiment herein described is provided with 12 compartments, and the timing disks are provided with only six 85 tripping cams, it is necessary that the tripping cams, of one disk be placed in staggered relation with the tripping cams of the adjacent disk so that the tripping cam on every disk will be coming into operative 90 relation with the associated tripping plunger just at the instant that the card is being analyzed. Otherwise some of the tripping plungers would be operated at an instant when the point of the disk midway between adjacent cams would be opposite the plunger, and no setting of the tripping cam would take place. The number of tripping cams could be either greater or less than shown, if desired.

From the foregoing the operation of the entire machine shown in Figs. 1 to 4 will be readily understood and need now be only very briefly summarized as follows:

By means of the reciprocating picker 105 blade 34, each card is fed from the lower part of the magazine hopper 18 to the roller 38 whence it is carried between the perforated plates 51, after which the pin box of the analyzer is lowered and the plunger pin 110 85 and the tripping plunger 171 associated with the compartment to which said card is destined, are operated, thereby bringing about the setting of the tripping cam 140 associated with said compartment just as it 115 comes into operative relation with such tripping plunger. When this takes place the set tripping cam 140 and the card which causes its setting, respectively travel toward the operating arm 156 and the deflectors 100 120 associated with such compartment; and because of the relation between the location of the plunger setting, the remoteness of the compartment from the analyzer, and the speeds of travel of the set tripping cam and 125 the card, said tripping cam comes into operative relation with the operating lever 156 just before the card comes into operative relation with the deflectors, whereupon the set tripping cam operates the operating lever 130

and consequently the associated deflectors and deflects the card into the appropriate compartment. The operating cam immediately passes on and permits the deflectors to fall, so that a card immediately following the card thus deflected may pass over said deflectors for a more remote compartment. If such card was destined for the same compartment, the deflectors will be immediately 10 deflected again in the same manner just described.

As soon as the operating arm 156 has been operated, the tripping finger 145 engages the tripping pin 158 thus releasing the shoulder 15 147 from the detent pin 150 whereupon the tripping cam resumes its normal position. This operation is repeated until all of the cards are analyzed and deposited in their appropriate compartments.

20 In the alternative form of timing mechanism shown in Fig. 5 the tripping member 238 is similar to the tripping cams 138 except the former is not provided or supplied with a cam operating-edge, and is set by means of a setting plunger 240 pivoted at 241 to the tripping member and operated by the plunger core 242 slideable in the solenoid 243.

Each solenoid 243 is grounded at one end 30 247 of its wire upon the timing disk, and therefore to the frame of the machine. The other end 248 of the solenoid wire is electrically connected to one of a series of commutator plates separately mounted in the 35 insulating ring 251 mounted on a collar 252 mounted on the timing shaft 135. As the timing shaft rotates, the commutator plates come successively into contact with the spring brush 255 electrically connected to 40 the wire 89. To each tripping member 238 there is associated one solenoid 243 and one commutator plate 250.

The operation of the tripping member 238 is very similar to that of the tripping cam 45 138. The plunger pin 85 is lowered just as a commutator plate 250 comes into contact with the brush. This completes the circuit of the associated solenoid and the setting plunger 240 is projected and the tripping member is set. The brush 255, the solenoids, and tripping members are so arranged and timed that the tripping member actuated by a card in the analyzer destined for a certain compartment is just enough remote 55 from the arm 156 of such compartment. The construction and operation of the parts operated by the tripping cam 138 and the tripping member 238 are identical.

I claim as my invention:

60 1. In an apparatus of the character described, sorting stations; an analyzer; a deflector for each station; a sleeve for each

station; a core in each sleeve; a plunger fixed to each core and to bring about the actuation of said deflectors; and a solenoid 65 on each sleeve and electrically connected to the analyzer.

2. In an apparatus of the character described, sorting stations; an analyzer; a deflector for each station; revoluble settable 70 devices adapted to trip said deflectors; a sleeve-thimble for each station; a core in each sleeve; a plunger fixed to each core and adapted to set said devices; and a solenoid on each sleeve and electrically connected to 75 the analyzer.

3. In an apparatus of the character described, sorting stations; an analyzer; a deflector for each station; a rotary timing member for each station; settable devices on 80 each member adapted to trip said deflectors; brackets disposed at different positions near each timing member; a thimble on each bracket provided with a bore having an annular shoulder; a sleeve in each bore; a core in each sleeve; a spring disposed between said core and shoulder; a plunger fixed to each core and passing out through said bore to set said devices; and a solenoid on each sleeve and electrically connected to 90 the analyzer.

4. In an apparatus of the character described, the combination of a plurality of sorting stations; an analyzer; an individual deflector associated with each station; a rotary timing shaft disposed longitudinally of the machine; timing disks on said shaft, one for each station; a plurality of settable tripping devices on each disk adapted when set to trip said deflector; brackets disposed at 100 different angles around said shaft and each provided with an opening thereon; a thimble provided with a longitudinal bore reduced at its inner end to form an annular shoulder, and provided with a threaded extension received in said opening; a nut by 105 which said extension is held in place; a sleeve fast in each core; a core slidably received in each sleeve; a coil spring disposed between said core and said shoulder 110 for holding the core retracted; a setting plunger fixed to said core by means of a threaded connection and passing outwardly through said bore and adapted when projected to set said settable tripping devices; 115 and a solenoid wound around each sleeve and having one end of its wire grounded on the frame of the machine and the other connected to the analyzer.
